Dec. 27

Addison Low assignor to Francis T. Low
and Francis T. Speake all of Albany, New York
Letters Patent No. 27, dated February 12th 1845

The schedule referred to in these Letters Patent and
making part of the same.—

To all whom it may concern: —

Be it known that Addison Low of Albany in
the County of Albany and State of New York have in-
vented or produced a new design for an ornamental
parlor stove, and I do hereby declare that the following
is a full, clear and exact description of the same. —
reference being had to the accompanying drawings, making
part of this specification, in which fig. 1st H. 1. represents
a stove constructed after my design, and figs. 2. 3. 4. 5. 6.
7. 8. 9. 10. & 11 of pl. 1. and figs. 12 & 13 of pl. 2. exhibit on
a larger scale, the detail ornaments. Fig. 2nd is the lower
& fig. 3rd the upper, member of the middle cornice a. a. —
fig. 4th is the upper cornice b. b. fig. 5. is the border
of the hearth. Fig. 6. is the front, and fig. 7. the end
of the top C. C. Fig. 8. is the ornament filling the space
between the apertures of the registers of the front fire
door d. d. Fig. 10. is the plate g. below the upper cornice.
Fig. 11. is the end door f. Fig. 12 H. 2nd is the figure

Dec 27

of an American Eagle, surmounting the shield of the United States. Fig. 13. is the ornament upon the top of the fire box, between the scrolls which form the flames, representing a vase, with foliage.

What I claim as my invention, and desire to secure by letters patent, is the design for an ornamental Parlor Stove, represented in the accompanying drawings.
